A. E. JURY,

FRICITION AND FLEXING APPARATUS FOR TESTING MATERIALS.
APPLICATION FILED JUNE 18, 1919.

1,344,301.

Patented June 22, 1920.

UNITED STATES PATENT OFFICE.

ALFRED E. JURY, OF NEWARK, NEW JERSEY, ASSIGNOR TO MORGAN & WRIGHT, A CORPORATION OF MICHIGAN.

FRICITION AND FLEXING APPARATUS FOR TESTING MATERIALS.

1,344,301.

Specification of Letters Patent. Patented June 22, 1920.

Application filed June 18, 1919. Serial No. 305,153.

To all whom it may concern:

Be it known that I, ALFRED E. JURY, a citizen of the United States, residing at Newark, county of Essex, State of New Jersey, have invented certain new and useful Improvements in Friction and Flexing Apparatus for Testing Materials, of which the following is a full, clear, and exact description.

10 This invention relates to improvements in apparatus employed in ascertaining the effect of friction or flexing or both upon materials, such, for example, as fabric, rubber, or the like. In the use of the apparatus the material is subjected to the action of the apparatus for a definite length of time and is then removed and subjected to the action of a strength testing machine to ascertain the effect upon the fabric of the friction or 20 flexing or both.

The invention will be understood by the accompanying drawings in which:

Figure 1 is a side elevation of an apparatus embodying the improvements;

25 Fig. 2 is a fragmentary view, in perspective, and on an enlarged scale, illustrating the fabric holding means; and

Fig. 3 is an enlarged side elevation of the fabric holding means when adapted for 30 exerting friction alone upon the material.

The apparatus consists of a frame comprising the bed A, from which rise the standards a, the latter supporting cross members b, each cross member being formed 35 with an apertured boss c, for the purpose hereinafter described.

Slidably mounted in the body A is a plate B provided at one end with a suitable cross-head d—d adapted to receive the end of a 40 connecting rod E, said rod also being connected to a crank pin f on a drive wheel F. By this means a reciprocating movement will be imparted to the plate B, and the parts carried by it, upon the rotation of 45 wheel F.

Mounted upon the plate B are blocks h, four of such blocks being shown, each being disposed immediately below a pressure block i carried by a rod k. These rods are 50 slidably mounted in the apertured bosses c, rotary movement of the rods k being prevented by set screws N engaging grooves or channels in the rods k. The rods k are extended upwardly above the cross-members 55 b and are adapted to receive weights W

which rest upon plates M carried by the rods.

When it is desired to subject the fabric or other material to friction alone a piece of the material is secured to either one of the blocks h, i, and the slide plate B is reciprocated so that the material is subjected to a rubbing action between the two blocks under a pressure determined by the weight or weights carried by the supporting plate 60 m. The material may be secured to the block by means of the pins p as shown in Fig. 3, or by any other suitable means such as the clamping frame r' illustrated in the said figure in which the clamping pressure 70 upon the fabric is regulated by means of a screw or screws t acting upon a movable block or blocks v. In the said figure a piece of fabric is held by each block so that in the operation of the machine the two pieces 75 of fabric are rubbed upon each other.

When it is desired to subject the material to flexing, one end of a strip of material may be impaled near one of its ends upon pins p projecting upwardly from each holding block h, the material then being brought toward the opposite end of the block and folded backwardly, the folded end being clamped against one side face i' of the pressure block i by means of a clamping frame 80 r, the pressure of said clamping frame upon the material being effected by means of a set screw s. The reciprocation of the plate B will then subject the material to a flexing action, and by means of the weights this 85 flexing action may be combined with a desired degree of friction or abrading action between the contacting faces of the material.

Having thus described my invention, 95 what I claim and desire to protect by Letters Patent is:

1. An apparatus of the character described, superposed engaging members for the material to be treated, each member being adapted to hold one end of a folded piece of flexible material, means for moving one of said members in parallelism with a face of the material to subject the latter to friction and flexing, the second member being adapted for movement in a direction transversely of the direction of movement of the first named member, and means for moving said members toward each other in the last mentioned direction. 100 105 110 115

2. In apparatus of the character described, a reciprocable table, a bar slidably movable toward and from the table, opposed engaging members for the material to be treated, one member being carried by the table and the second member by the bar, each member being adapted to hold one end of a folded piece of flexible material, means for applying pressure to the bar, and means for reciprocating the table.
3. In apparatus of the character described, a table, a bar movable toward and from the table, two opposed members for holding the material to be treated, one member being supported by the bar and the second member by the table, means for ap-

plying pressure to the bar, means for reciprocating the table, and means whereby the pressure upon the bar may be adjusted.

4. In apparatus of the character described, a frame, a table slidably mounted in said frame, a bar adapted for free end-wise movement in said frame, means for moving said bar in one direction, means carried by the said bar and table for holding a folded piece of flexible material intermediate them, and means for reciprocating the table independently of the bar to subject the material to a flexing action.

Signed at Newark, New Jersey, this 13th day of June, 1919.

ALFRED E. JURY.
